CLAIM

The ornamental design for a fencing bib as shown and described.

DESCRIPTION

FIG. 1 is an elevation view of a first embodiment of a fencing bib in accordance with the present invention;

FIG. 2 is an elevation view of a second embodiment of a fencing bib in accordance with the present invention; and, FIG. 3 is another elevation view of the second embodiment showing the fencing bib in use by a fencer in accordance with the present invention.

The broken lines in the Figures depict portions of the fencing bib that form no part of the claimed design. The broken lines in FIG. 3 depicting a fencer represent environmental subject matter that forms no part of the claimed design. The bibs are flat with no ornamentation on the rears thereof.
